ARTEMAS B. EDMANDS, OF MILFORD, MASSACHUSETTS.

KNOT-TYING DEVICE.

1,112,367.

Specification of Letters Patent. Patented Sept. 29, 1914.

Application filed May 5, 1913. Serial No. 765,468.

To all whom it may concern:

Be it known that I, ARTEMAS B. EDMANDS, a citizen of the United States, residing at Milford, in the county of Worcester and State of Massachusetts, have invented certain new and useful Improvements in Knot-Tying Devices, of which the following is a specification.

My present invention relates to improvements in knot-tying devices, and the purpose of my invention is to provide a mechanism, by which the loose ends of the thread may be cut off neatly, and of approximately the same length, and a weaver's knot quickly and accurately tied.

I accomplish these results by the mechanism shown in the accompanying drawings, in which—

Figure 1 is a view of my device looked at from above. Fig. 2 a sectional view through the plane 2—2 of Fig. 3. Fig. 3 is a vertical section through the plane 3—3 of Fig. 1. Fig. 3½ the spring which restores the trigger and hook needles to their original position after the trigger has been pulled. Fig. 4 an end elevation. Fig. 5 a side elevation showing how the mechanism is held by the hand. Fig. 6 a section of the spring actuated thread guide on plane 6—6 of Fig. 7. Fig. 7 a sectional view of the same on the plane 7—7 of Fig. 6. Fig. 8 a detailed drawing of a part of the cutting-off mechanism and a portion of one hook needle. Fig. 9 a top view of a portion of my invention, showing the hook needles, the operation of the thread guide, the cutting off mechanism and the respective positions of the threads just before the thread is detached from the guide. Fig. 10 a view of the same at a later period of the tying operation. Fig. 11½ the method by which the hook needle f' holds one end of the thread. Fig. 11 the arrangement of the thread just before the knot is drawn tightly, showing the method of looping the thread. Fig. 12 shows the completed knot before tightening.

The various parts of the mechanism are indicated by the same letters throughout the several views.

My invention is designed to be held closely in the left hand of the operator, and it embodies substantially, features for guiding and locating in their proper positions with reference to each other the two threads to be tied; two hook needles operating in planes at right angles to each other and in

fixed relation to each other and to the members of the thread and adapted by manipulation of the trigger to catch and put the threads into proper relation for the tying of the knot; and two thread cutters for cutting off the ends of the thread.

In the several figures a represents the body or framework of a hollow box or casting, approximately rectangular in horizontal section and having a lateral projection as seen at the top of the drawings in Figs. 1 and 2.

a' is a flange, or projection from one side of the case a , serving as a seat for the member a'' to which is affixed a handle a^6 seen best in Fig. 5, provided with slots a^7 — a^8 for the reception of a strap and buckle a^8 — a^9 adapted to secure the device upon the hand of the operator. The member a'' is adjustable upon a' by means of a slot a^4 , and the screw a^5 . The bend a^2 seen in Fig. 1 limits the movement of a'' .

Upon the interior of the case a , and at the interior angle formed by the lateral projection above mentioned, is the angular member h , Fig. 2, having the support h' which carries the stud b^2 supporting the shaft b' and also forms the support h^2 of the stud i supporting the shaft e^3 , these two shafts b' and e^3 being at right angles to each other. The shaft b' is supported by the stud or screw c at the outer end and by the similar stud b^2 at the inner end, and the shaft e^3 is supported by the stud i ; the shaft b' is revolvably mounted on the stud b^2 and the pin c , and this shaft b' has fixed upon it the member d — d' and the member m' which shaft and members are all integral with and operated by the trigger m , seen best in Fig. 3. The member d — d' consists substantially of a longitudinal piece of metal terminating at one end in a receptacle d^2 for the hook needle f — f' , and at the opposite extremity in the piece d' which is upon one face made a segment of a beveled gear. The shaft e^3 is revolvably mounted by means of the pin i fixed in the member h^2 at one end, and projects through and is supported by the case a at the other end, as shown in Fig. 2.

Integral with the shaft e^3 and forming a portion of it is the segmental beveled gear e' in mesh with the beveled gear d' ; and forming also a part of the shaft e^3 and integral therewith is the arm e , having at its extremity the projection e^2 serving as a re-

ceptacle or holder for the other hook needle g , the arm e and the arm d being substantially counter-parts of each other and operating simultaneously in planes at right angles to each other by means of the beveled gears $d'-e'$. The two shafts e^3 and b' with their connected beveled gears and hook needle carriers are operated by the trigger m of Fig. 3, which is integral with the shaft b' as above stated.

The gear d' is about two-fifths larger pitch diameter than the gear e' so that the hook needle g will have a somewhat longer travel than the needle f .

m' is a segmental beveled gear which meshes with a similar segmental gear n' , which is fixed upon the revoluble stud n , a vertical view of which is seen in dotted lines in Fig. 4. It will thus be seen that when the trigger m is pulled, the beveled gears $e'-d'$ are brought into operation, each carrying its respective hook needle and at the same time the beveled gears $m'-n'$ act to rotate the stud n as above stated. The trigger m and its connected parts are restored to their normal position by the coiled spring S^2 of Fig. 3, this spring being fixed to the shaft b' by the tongue S^3 and having its other end S^4 anchored to the frame, as seen in Fig. 4.

x , seen best in Figs. 1 and 9, is a stationary shear blade fixed upon the frame of the device, and y is a movable blade, the two serving for cutting off the thread 1 before the knot has been tied, as hereinafter set forth. The blade y is fixed upon and operated by the stud n , which is itself operated by the beveled gears $m'-n'$, above described.

It will be noted that the stud n which carries the blade y of the upper pair of shears is held firmly down by means of the spring o , seen best in Fig. 3, which spring bears against the upper face of the off-set n' , Figs. 3 and 4, thus holding the blade y firmly against its opposing blade x .

w^3 seen in Fig. 5 is a projection from the top of the device, and carries the stud n and the shears $x-y$, and between this projection and the posts $w-w$, there is a space or opening w^4 at the bottom of which is a groove or channel w^2 for one of the threads as seen best in Figs. 1 and 4, while w' , Figs. 1 and 11, is a similar groove for the other thread. It will be noted in Figs. 3 and 4, that the stud n is perforated with the hole f^2 . This permits the hook needle f' to pass entirely through it when the trigger m is pulled back to its limit, and as the perforation f^2 is made considerably larger than the hook needle f' , there is no interference with the operation of the blade y , as the throw or travel of y is itself very limited.

The end of the other thread 2 before the knot is tied is cut by the shears $j'-p$ shown best in Fig. 4, p being the stationary blade and j' the movable blade thereof. This movable blade j' is fixed upon the member j and slides within the plate k which is itself fastened to the frame of the knot-tier, and this blade j' is seen best in Fig. 8, which figure also discloses its method of operation. Fixed upon the beveled gear e' which forms part of the needle carrier e , and a little off the center 75 on which said beveled gear revolves, is a pin or stud e^4 , seen also in Figs. 1 and 2, which pin engages the slot e^5 in the member j and a partial revolution of the beveled gear e' causes the member j with the blade j' 80 to travel forward sufficiently to shear off the projecting end of the thread by means of the blade p and j' . The position of the thread just before shearing is shown in Fig. 9 and just after pulling the trigger is shown 85 in Fig. 10.

The plate k which retains in place the member j with its connected blade j' is split longitudinally, as shown in Fig. 4, and the member k' above the split is bent inward so 90 as to force it by a spring engagement closely against the blade p so as to insure a clean cut.

$w-w$ are posts rounded on their outer faces, and having a space w' between them 95 for the passage of the hook needle f' and the reception of one of the threads, and together serve as a thread holder, as seen best in Figs. 9, 10 and 11.

The member s , Figs. 6 and 7, serves as a 100 thread guide, operating to insure the proper placing of the thread for its engagement by the hook needle. The member s is mounted so as to revolve upon the stud t , and has a spring u to bring it back into the position 105 from which it has been moved by the tension of the thread in the proper placing of the same before tying the knot. The backward motion of s is limited by the stud s' .

x^2-x^3 , Figs. 1, 3 and 4, is an eyelet fastened by the flat shank x^2 to the side of the projection w^3 and serves to hold the thread 1 in proper relation to the shears $x-y$. This eyelet is for the sake of clearness, omitted from Figs. 9, 10 and 11.

q seen best in Figs. 3 and 4, is a spring clamp fastened to the bottom of stationary blade p of Figs. 1 and 2, and having its upper end projecting above said blade, as shown in Fig. 3. The upper end of the 110 blade p , Fig. 4, has its corner cut away at the inner portion, adjacent to the face of q , so as to facilitate the admission of one of the threads, as explained later. This plate q is secured to p at its lower end so that it has 115 a spring contact at the upper end with the stationary blade p , thus forming a clamp serving to hold the thread 2 at proper tension as seen in Figs. 9 and 10.

Attention is called to the fact that the 120

end of the other thread 2 before the knot is tied is cut by the

under or concave surface of the needle f is cut away, as shown in Fig. 3 and also in Fig. 11 $\frac{1}{2}$ excepting at the upper end f' of the needle. This cut away space and full sized end f'' serves a very important function in holding the thread 1 while the loop is being formed, as will be shown hereafter.

The operation of my invention is as follows, and can be seen best by an inspection of Figs. 9, 10, 11, and 12. The device is held in the left hand, the hand going through the strap a^3-a^6 , the index or middle finger being in engagement with the trigger m , and the thumb resting upon the upper portion of the knot-tier and holding the thread 1. One end of the thread 1 is then passed through the space w' and thence through the guide loop x^3 above the shears $x-y$. The other thread 2 is drawn by the right hand between the clamp q and the stationary blade p and thence around the posts $w-w$ over the spring guide s , thence through the space w^4 and over the thread 1, the outer portion of the thread 2 being held in the right hand; the thread 2 is then drawn somewhat tightly by the right hand, forcing forward the spring guide s until the thread 2 slips off and s assumes its original position, as shown in Fig. 9 leaving the thread lying close to and around the base of the posts $w-w$. When this position is reached, the trigger m is pulled by the middle finger of the left hand, the two hook needles $f'-g'$ are thus brought forward, g' crossing over the outer or loose end of the thread 2, Fig. 10, and under the thread 1, and also under that portion of 2 lying between the posts $w-w$ and the clamp q . The pulling of the trigger m cuts off the thread 1 by the shears $x-y$ also the thread 2 by the shear $j'-p$.

The relative position of the threads just before the trigger is released is shown in Figs. 10 and 11 $\frac{1}{2}$. The needle $f-f'$ as it comes forward forces by reason of the shape of the head f' the thread 1 to one side, as shown in Fig. 10 and as the needle point f' advances it passes over the thread 1 as indicated by the dotted lines in Fig. 10. As soon as the threads have been cut off by the shears as above stated, the trigger is released and the needles $g-g'$ and $f-f'$ return to their original position by means of the spring s^2 .

As it is important that the main portion of the thread 1 should not be disturbed by the return of the needle $f-f'$ until the outer end of 1 is caught by the hook f' , I have provided a clearance for the main portion of the thread by cutting away the under portion of the needle $f-f'$, as shown in Figs. 3 and 11 $\frac{1}{2}$. As the needle $g-g'$ returns toward its original position it catches on its return path, first, that portion of the thread 2 which lies directly between the

clamp q and the posts $w-w$, and draws it backward in a loop as shown in Fig. 11. At the same time the needle $f-f'$ in its return catches with its hook the end of the thread 1 adjacent to the shears $x-y$ and 70 brings it back over the outer end of the thread 2 which is held by the right hand of the operator, the relative positions of the thread then being as shown in Fig. 11.

Fig. 11 $\frac{1}{2}$ also shows that that portion of 75 the thread 1 lying immediately below the shears $x-y$ is almost perpendicular so that the side barb of the needle $f-f'$ readily grasps it and draws it backward into the position shown in Fig. 11. It will also be 80 seen in Fig. 11 $\frac{1}{2}$ that the head or extremity of the needle $f-f'$ being of full size, serves to hold securely the end looped thread 1 as the needle $f-f'$ returns to its original position, so that the thread 1 is clamped by the 85 head f' of the needle $f-f'$ until the thread 2 is pulled from the posts $w-w$ in the final tightening of the knot.

The threads being in the relative position shown in Fig. 11, a slight pull of the right 90 hand upon the thread 2 slides the loop of the thread 2 off from the posts $w-w$ and leaves the ends in the relative positions shown in Fig. 12, the knot being then completed by pulling the thread 2 tighter by 95 means of the right hand of the operator, the thread 1 being retained by the thumb of the left hand.

Having now described my invention, which I claim and desire to secure by Letters Patent is:—

1. In a knot-tying device, a containing frame work; a trigger shaft revolubly mounted therein; a second shaft also revolubly mounted therein at right angles to 105 said trigger shaft; two needle-carrying arms, the one integral with said trigger shaft, the other integral with said second shaft and operating in planes at right angles to each other; two hook needles fixed one 110 upon each of said arms; a reciprocating trigger fixed upon said trigger shaft; bevel gears fixed one upon the inner end of each of said needle-carrying arms and in mesh with each other; a spring operating to return 115 said trigger and said needle arms and needles to their normal position when said trigger is released; and means for arranging the threads in such a position with reference to each other and to said needles that 120 said threads will be drawn by engagement with said needles into a weaver's knot.

2. In a knot-tying device, a containing frame work; a trigger shaft revolubly mounted therein; a second shaft also revolubly mounted therein at right angles to 125 said trigger shaft; two needle-carrying arms, the one integral with said trigger shaft, the other integral with said second shaft and operating in planes at right angles 130

4
to each other; two hook needles fixed one upon each of said arms; a reciprocating trigger fixed upon said trigger shaft; bevel gears, one upon the inner end of each of 5 said needle-carrying arms and in mesh with each other; a spring operating to return said trigger and said needle arms and needles to their normal position when said trigger is released; guides for placing the threads 10 in proper relation to each other for the formation of a weaver's knot by the engagement therewith of said needles, and separate shears mounted upon said containing frame work and operated by said trigger, 15 and serving to cut said threads to a proper length.

3. In a knot-tying device, a containing frame work; a trigger shaft revolvably mounted therein; a second shaft also revolvably mounted therein at right angles to 20 said trigger shaft; two needle-carrying arms, the one integral with said trigger shaft, the other integral with said second shaft and operating in planes at right 25 angles to each other; two hook needles fixed one upon each of said arms; a reciprocating trigger fixed upon said trigger shaft; bevel gears, one upon the inner end of each of said needle-carrying arms and in mesh with 30 each other; a spring operating to return said trigger and said needle arms and needles to their normal position when said trigger is released; two posts adapted to form a loop in one thread and having a space between 35 them for the reception of the second thread; a thread guide operating to place said second thread in proper relation to said first thread for the formation of a weaver's knot

and an eyelet serving to hold said first thread in position. 40

4. A knot-tying device comprising a frame, two hook needles revolvably mounted therein and moving in planes at right angles to each other, one of said needles moving in the arc of a circle and being of 45 full size at its free end and having a portion of its concaved surface cut away to form a clearance for the thread to be engaged by said needle and its free end being adapted to hold said thread for maintaining 50 proper relations to a second thread for the formation of a weaver's knot, journaling means for said needles positioned transversely of and perpendicular to each other and means for operating said needles. 55

5. In a knot-tying device, two revolvably mounted hook needles adapted for movement in planes at right angles to each other, one of said needles being of full size at its free end and having a portion of its concaved surface cut away to form a clearance for the thread to be engaged by said needle and the free end of said needle adapted to hold said thread for maintaining the proper relations to a second thread for the formation of a weaver's knot, journaling means for said needles, one of said journaling means being positioned transversely through the other journaling means. 60

In testimony whereof I affix my signature 65 in presence of two witnesses.
